CLAIM

The ornamental design for a disposable animal litter container, as shown.

DESCRIPTION

FIG. 1 is a perspective view of a disposable animal litter container showing my new design in its closed position; FIG. 2 is a perspective view showing the design in its open position;

FIG. 3 is a front elevational view;

FIG. 4 is a top plan view;

FIG. 5 is a left side elevational view, the right side being a mirror image thereof;

FIG. 6 is a rear elevational view; and

FIG. 7 is a bottom plan view.
